WORK FEEDING DEVICE

Theodore E. Mead, Wilmette, Ill.

Application December 6, 1943, Serial No. 513,196

15 Claims. (Cl. 10—162)

This invention relates to a work feeding device, and more particularly to a device for automatically feeding work to a position where it is securely held and then discharging each piece of work before the next piece is advanced.

An object of the invention is to provide a device which will hold individual pieces of work in position for tapping, drilling, or other mechanical processing and which will discharge pieces therefrom so as to permit a great number of pieces to be processed in a short time. Another object is to provide such a device which will hold the pieces securely and positively and which will be infallible in selecting but a single piece for presentation to the work-holding position.

Another object is to provide a device for feeding into work-holding position pieces which are of irregular thickness in such manner that the pieces are firmly held and always in correct position for working.

Another object is to provide a device having improved mechanism for receiving individual pieces from a magazine, and having improved means for advancing the pieces into work-holding position. A more specific object is to provide such improved mechanism and means which will permit pieces having sharp edges to be held in the device but which will not serve to harm or break off these sharp edges.

Another important object of the invention is to provide means for assuring the discharge of the work pieces from the work-holding position when the holding mechanism is released and before the device has operated to select and present the succeeding piece.

Other objects and advantages will appear as the specification proceeds.

The invention is illustrated by the accompanying drawings, in which—

Fig. 1 is a perspective view of one embodiment of the device; Fig. 2 is a broken sectional view in elevation, the section being taken as seen from line 2—2 of Fig. 1; Fig. 3 is a broken sectional view in elevation, the section being taken as seen from line 3—3 of Fig. 2; Fig. 4 is a fragmentary view similar to Fig. 3, but showing a somewhat modified structure; Fig. 5 is a sectional view taken along the same line as Fig. 4, but showing the reciprocating structure in advanced condition with a work piece in work-holding position; Fig. 6 is a fragmentary sectional view similar to Figs. 3 and 4, but showing a modified structure; Fig. 7 is a view like Fig. 6, but showing the reciprocating structure in advanced condition with a work piece in work-hold-

ing position; Fig. 8 is a plan view of another modified structure; Fig. 9 is a view like Fig. 8, but showing the reciprocating structure in advanced position; Fig. 10 is a plan view of still another modification which utilizes pieces having sharp edges; Fig. 11 is a view like Fig. 10, but showing the reciprocating structure in advanced position; Fig. 12 is a detail sectional view taken as indicated at line 12—12 of Fig. 10; Fig. 13 is a detail sectional view taken as indicated at line 13—13 of Fig. 11; Fig. 14 is a sectional view in elevation of still another modified structure which utilizes elongated pieces; Fig. 15 is a fragmentary sectional view taken along the same line as Fig. 14, but showing the reciprocating structure in advanced position; Fig. 16 is a detail plan view of the modification shown in Figs. 14 and 15; Fig. 17 is a plan view of still another modified structure; Fig. 18 is a view like Fig. 17 except that it shows the reciprocating structure in advanced position; Fig. 19 is a detail sectional view taken as indicated at line 19—19 of Fig. 18; Fig. 20 is an enlarged plan view of the pivoted member and associated structure shown in Fig. 18; and Fig. 21 is a view like Fig. 20 except that it shows the pivoted member in piece-receiving position as illustrated in Fig. 17.

As illustrated in Figs. 1 to 3, the improved device includes a base or frame structure A, reciprocating structure B which provides with the frame structure a pair of jaws, a magazine C which presents the pieces for feeding, mechanism D for actuating the reciprocating structure, and apparatus E for dislodging the pieces after the holding operation is over.

The frame structure A may be of any suitable form and construction. As shown in Fig. 1, this frame includes a base plate 10 having the edge flanges 10a by which it may be secured to a floor or support. The main frame body 11 has a central channel 12 running lengthwise of this body. Near the top of this channel is a cut-out portion 13 to accommodate the dovetail fitting of the slide 30, later to be described. Mounted on the side of channel 12 is an inclined piece 14 on which the pieces may slide from the device after the operations on them are completed.

Mounted on the frame body 11 and at the far end of the frame is a jaw member 15 having a V-shaped serrated face. The face of this jaw may, of course, take other special forms when so desired. This jaw member provides one of the jaws which serve to hold the individual pieces in work-holding position.

The reciprocating structure B includes the slide

which has its edges inclined to provide with the cut-out portion 13 of the frame a dovetail fitting. The top of slide 30 provides a seat or support 31 on which the individual pieces may rest as the device operates to present them to work-holding position, and the top of this slide may be even with the top of the frame body 11. Suitably, the central portion of the forward end of slide 30 may be cut away as indicated at 32, so as to prevent interference with the processing operations, such as the drilling of the central portions of the pieces.

Mounted on top of the slide 30 is the bar 35 which at its forward end provides a jaw adapted to engage the rearward edge of the pieces as they come from the magazine.

The magazine may be of any desired structure suitable for holding the pieces to be worked for successive delivery. The magazine C, which is best illustrated in Fig. 1 of the drawings, includes a tube-like container 36 slightly inclined with the frame structure and having its bottom edge parallel with the plane of the top surface of the frame. The bottom opening, through which the pieces are discharged from the magazine, is immediately over the seat 31 of the slide 30 when the reciprocating structure is in retracted position. The magazine is supported by means of the bracket 37 which may be attached to the frame A, or to other structure fixed with respect to this frame. The magazine may contain a number of flat pieces, such as metal washers, for example, in vertically-stacked relation, so that as soon as one is removed from the delivery end another falls into place ready for removal on the succeeding stroke.

The rear portion of the slide 30 may be attached to the piston 38^a of the air cylinder 38 which forms a part of the actuating mechanism D. A spring 39 is provided for retracting the piston and therefore the slide 30 when the air pressure is relieved on the cylinder.

The apparatus E for dislodging the pieces after being held includes the air tube or nozzle 40 which has its mouth directed at the rear portion of the piece when the piece is in the work-holding position, as indicated in dotted lines in Fig. 1. This tube 40 may be mounted to the frame as by the bracket 41, and is connected to the air line 42 which is connected through the valve 43 to a source of air pressure. The valve 43 has a button 44 which when depressed operates to open the valve and permit the passage of air therethrough. Cooperating with valve 43 is a detent 45 pivotally mounted on the under side of the slide 30. Detent 45 is arranged to move about its pivot to pass over button 44 without depressing it when the slide is advanced, but to momentarily depress this button as it contacts this button on the rearward movement of the slide.

A secondary structure which aids in the positioning and dislodgement of the piece is the spring 46 which in this embodiment is mounted on the bracket 37 and projects downwardly so that its sharpened point 48 rests on the rearward portion of the piece when the piece comes to work-holding position.

In many instances, it is important that the jaws which engage the piece in the holding function be thicker than the piece being held so that a firm hold may be attained. This is made possible while still permitting the selection of but a single piece for advancement into work-processing position by the provision of structure, such as the height bar 50 positioned on the top of the

frame A and directly under the mouth of the magazine. This bar is cut away at its central portion, as indicated at 51, for the purposes of permitting the bar 35 secured to slide 30 to pass therethrough, but as clearly seen at Fig. 2 of the drawings, this bar is effective to support the lowermost piece in the magazine above the supporting surface 31 of slide 30 and at a position such that the top surface of this lower piece is even with or above the top surface of the bar 35. (See Fig. 3.) Forward of the magazine, the height bar 50 is terminated, and near its forward edge its top surface may be tapered as indicated at 52.

In the operation of this embodiment, the magazine is filled with pieces and the device started in the position indicated in Fig. 1 of the drawings. The lowermost piece 53 will rest on the height bar 50. Then the operator may operate any suitable valve (not shown) to admit air under pressure to the cylinder 38. This serves to advance the piston 38^a and therefore to advance the slide 30, causing the jaw provided by bar 35 to engage the rear edge of the piece 53. As the slide moves forward, the bar 35 passes through the opening in the height bar 50 and urges the piece 53 forward. When the piece passes beyond the end of height bar 50, it falls down onto the seat or support 31 on the slide 30. Continuing the forward movement, the piece is moved toward and brought into contact with the jaw 15. With continued pressure delivered by the cylinder 38, the piece is held in firm position between the two jaws and resting on the support 31. At this stage, any desired operations or processing steps may be performed on the piece.

When it is desired to release this piece and present another, the operator operates the valve to release the air pressure on cylinder 38, and the spring 39 operates to retract the piston, withdrawing the reciprocating mechanism in its rearward stroke.

During the time the piece is assuming its work-holding position, the spring finger 46 serves to prevent the rearward edge from kicking up and when the reciprocating structure is being withdrawn, this spring finger serves to prevent movement of the piece following the slide.

However, a principal factor in dislodging the piece from the reciprocating structure upon rearward movement of this structure is the apparatus E which, when the detent 45 engages the button 44, serves to deliver through nozzle 40 an air blast directly against the piece causing it to be dislodged from the reciprocating structure and fall down the chute provided by the channel 12 and the inclined piece 14.

When the air cylinder is again operated to advance the slide 30, another piece is selected from the mouth of the magazine and is handled in the same manner.

In addition to being thicker than the individual pieces, the bar 35 may have its jaw face inclined with the vertical so that the upper edge protrudes and extends over the piece when held in processing position. This feature will be made more clear in connection with the modified structure which will next be described.

As illustrated in Figs. 4 and 5, the jaw member 60 may have an inclined face 61, and the jaw member 62 may have the inclined face 63, the faces 61 and 63 being inclined inwardly toward their tops. As in the embodiment previously described, the jaw member 62 is mounted on a slide 30^a, and a height bar 50^a serves to maintain the top of the lowermost piece in the maga-

zine at a point above the top of the jaw member 62.

When the jaw 62 is brought up to confine the piece 53^a in processing position as indicated in Fig. 5, the surfaces 61 and 63 engage the top of the piece and in this way tend to prevent its edges kicking up and tend to prevent its getting in any other position except flat against the supporting seat 31^a of the slide 30^a.

Shown in Figs. 4 and 5 is a bracket 65 which is mounted on the top of the jaw member 60. This bracket extends rearwardly over the work-holding position of the piece and is provided with a drill bushing 66 through which a drill or other tool may be inserted to process the piece.

In the operation of the embodiments shown in Figs. 1 to 5, it will be apparent that when the moving jaw engages the lowermost piece presented by the magazine, the top of the jaw will engage the piece at a point below its top surface, so that there is no danger of advancing more than one of the pieces even though the jaw member is thicker than the piece.

In the embodiment illustrated in Figs. 6 and 7, the pieces 70 are of irregular thickness, having a relatively thick hub portion and a relatively thin rim portion. Here the jaw 60^b has a lateral groove or recess 61^b which is V-shaped in cross section. The jaw 62^b has a substantially similar lateral groove or recess 63^b, and when the slide 33^b is advanced the groove 63^b receives the thin rim of the piece 70 and advances it from a position adjacent magazine C^b into processing position as seen in Fig. 7 where the jaw 60^b also receives the forward rim of the piece 70. This form of engagement serves to hold the piece in the proper position and prevents it from tilting or otherwise losing this proper position.

Figs. 8 and 9 show an embodiment which includes a magazine C' which has its lower portion curved so that the pieces, such as the nuts 70', are delivered from the magazine laterally onto the reciprocating slide 30'. The magazine C' is secured to one side of the frame A' and on the other side of this frame is a stop piece 76 which is provided at its face with a spring 77 which serves to cushion the blow of the nut pieces 70' as they pass laterally out of the mouth of the magazine in the operation of the device; also this spring member serves to position the last of the pieces to be issued from the magazine so that when the slide 30' is advanced, the jaw 62' will engage the piece squarely and so can move it forward without any extraneous movements of the piece. As the slide 30' advances, the piece is moved under the spring finger 46' which functions in much the same way as the spring 46 mentioned in connection with the first embodiment described. When the slide has reached the limit of its travel, the piece will be confined between the jaws 62' and 60'. Upon the rearward movement of the slide, the piece will be dislodged and discharged as previously described.

Figs. 10 to 13 illustrate an embodiment which is well adapted to the handling of pieces having sharp edges that are subject to injury if handled in ordinary vice-like structures. Here the pieces 70^c having the V-groove 21 are disposed in the magazine C^c. A wedge-shaped element 22 of the magazine engages the groove 21 and so maintains the pieces in alignment as they pass through the magazine. From the magazine, the pieces are discharged laterally onto the seat 31^c of the slide 30^c. This slide has jaw structure which extends

along the rearward end 23 of the seat and also along a side edge 24 of the seat. The jaw along the side edge of the seat is made slightly longer than the piece, so that when the slide is extended (see Figs. 11 and 12), the sharp edge of the piece is not pressed hard against the jaw 60^c. While in this position, the piece is resting on the seat 31^c and is enclosed on two sides by the jaw structure of the slide member and on two sides by the jaw structure which is secured to the frame. Thus, the piece is secured against turning or otherwise getting out of position while at the same time the delicate edge is not caused to be injured. In this embodiment also there is a spring finger 46^c which serves to guide and hold the piece, and a tube 40^c is provided through which compressed air may be discharged to dislodge the piece at the appropriate time.

Figs. 14, 15 and 16 illustrate an embodiment which is particularly effective in connection with elongated pieces 70^d which are stacked end to end in the magazine C^d. The lower portion of magazine C^d is vertical and discharges the pieces onto the seat 31^d of slide member 30^d. On each side of the frame A^d are the spring fingers 25 mounted by means of the brackets 26. As seen more clearly in Fig. 16, these fingers extend about and hold the piece which has just issued from the mouth of the magazine, preventing it from falling over. When the slide is extended, the jaw 62^d moves the piece 70^d out of the grasp of fingers 25, passing it on to its position against the jaw 60^d. The finger 46^d aids in dislodgment of the piece from the reciprocating slide when the slide is retracted. In this, as well as all other of the embodiments shown, the apparatus for utilizing an air blast for dislodging the piece can be employed.

Still another embodiment of the invention is illustrated in Figs. 17 to 21. Here the magazine C^e is mounted on the frame A^e so that the pieces 70^e, which may be small cylinders or the like, are passed laterally from the magazine into the reciprocating structure. A spring finger 27 serves to keep the pieces in line. On the reciprocating slide 30^e, jaw member 62^e is pivotally mounted. The mouth 28 of this jaw member is recessed so that it may receive therein the piece which issues laterally from the magazine.

The jaw member 62^e has an arm 29 to which the piston 81 of cylinder 80 is pivotally attached. The cylinder itself is pivotally mounted in the frame. A spring 82 serves to resist rearward movement of the piston near the end of its return stroke, and a spring 83 which is stronger than spring 82 resists forward movement of the piston near the end of its advance stroke.

As illustrated in the drawings, the pieces 70^e may have the top flanges 71, and when these pieces are received in the jaw member 62^e, the flanges 71 may rest on top of member 62^e without injury or interference and there need be no contact of the piece with the slide 30^e. A jaw member 60^e is provided which is complementary to the jaw structure provided by the member 62^e. The operation of this device is as follows:

With the pivoted jaw member 62^e in the position illustrated in Figs. 17 and 21, a piece from the magazine C^e passes directly into the mouth 28 of the jaw member where it is supported through the engagement of the flange 71 with the top of this member. As the slide 30^e is first advanced, the pivoted jaw member 62^e retains its same angular position and moves along with the slide to remove the piece from its position adjacent the mouth of the magazine. After this jaw has

passed the mouth of the magazine, the bar 72 mounted on the slide 30⁴ operates to prevent further pieces from issuing out of the magazine. During this initial movement, the spring 82, being relatively weak, yields. However, when the slide advances further, the spring 83, which is stronger, tends to be compressed and this serves to rotate the jaw member 62⁴ about its pivot and bring it into the angular position shown in Fig. 20. This member does not continue to move about its pivot because of the stud 73 which limits the pivotal movement, and upon further movement of the slide this jaw member moves straight forward, presenting the piece directly into the mouth of the complementary jaw member 60⁴. The piece is thus held between these jaws until the slide is actuated for retraction. During the initial portion of the rearward movement of the slide, the jaw member 62⁴ retreats without turning, being restrained by the spring 83 and the stud 73, and the apparatus E⁴ for delivering an air blast can come into operation to dislodge the piece. Upon continued rearward movement of the slide, the piston 81 will come to be actuated by the spring 82 and thus turned into the angular position first described and illustrated in Fig. 21. In this position, it can receive another piece from the magazine and the operation may be repeated.

The foregoing detailed description has been given for purposes of explanation only and no limitation is intended to be understood therefrom. It will be apparent that many modifications and changes may be made without departing from the spirit and scope of the invention.

I claim:

1. A work feeding device comprising a magazine adapted to contain a plurality of work pieces, reciprocating mechanism for presenting individual pieces from said magazine to processing position, said mechanism including a slide upon which said pieces rest when in processing position, and means actuated by the return movement of said reciprocating mechanism for discharging compressed air against said piece to aid in dislodging the same from said slide.

2. A work feeding device comprising a frame, a magazine mounted on said frame, a work-holding jaw secured to said frame, a slide mounted for reciprocating movement in said frame beneath the discharge end of said magazine, said slide being effective when it is advanced for moving a piece from said magazine forwardly and against said jaw, and spring means engaging said piece when in position against said jaw for aiding in dislodging said piece from said slide when the slide is retracted.

3. A work feeding device comprising a magazine adapted to contain a plurality of work pieces, a pair of opposing jaws, a reciprocating structure carrying one of said jaws thereon and providing a bottom support for successive pieces as they are moved into work-holding position between said jaws, said one jaw being effective as said structure is moved forwardly to push one of said pieces from said magazine tightly against the other of said jaws in which position it is disposed on said support and held between said jaws, and means for restraining said piece from rearward movement with said structure when said structure is retracted.

4. A work feeding device as called for in claim 3 wherein said means includes means for delivering a blast of air against said piece, and valve means actuated by the return movement of said structure for operating said air blast delivering

means to thereby restrain said piece from rearward movement with said structure.

5. A work feeding device comprising a magazine adapted to contain a plurality of work pieces of disk-like character in vertically-stacked relation, a pair of opposing jaws, a reciprocating structure carrying one of said jaws and providing a bottom support for pieces as they are moved into work-holding position between said jaws, said one jaw being of greater thickness than said pieces and having an inclined face so that its upper edge protrudes forwardly beyond its lower edge, said one jaw being adapted when said structure is advanced to urge one of said pieces forwardly from said magazine and against the other of said jaws in which position it is disposed on said support and held between said jaws, and means for maintaining the lowermost of said pieces in said magazine above said support so that its top edge is above the top edge of said one jaw until moved from said magazine through the operation of said structure.

6. A work feeding device comprising a magazine adapted to contain a plurality of work pieces in vertically-stacked relation, a reciprocating structure providing a support on which a piece may rest when in position for processing, a jaw carried on said structure, a jaw cooperating with said jaw opposite said jaw and disposed in fixed position with respect to said magazine, said jaws being of greater thickness than said pieces and having their faces protruding toward each other at their upper edges, said first-mentioned jaw being effective when said structure is advanced to move a piece from said magazine and into processing position between said jaws, and a height bar maintaining said pieces above said support to the extent that only one of the pieces in said magazine is contacted by said first-mentioned jaw as said structure is advanced to cause the jaw to move a piece therefrom.

7. A work feeding device comprising a magazine adapted to contain a plurality of work pieces in vertically-stacked relation, a reciprocating structure providing a support on which a piece may rest when in position for processing, a jaw carried on said structure having a thickness greater than the thickness of said pieces, a fixed jaw opposite said jaw and cooperating with said jaw, said first-mentioned jaw being effective when said structure is advanced to move a piece from said magazine and into processing position in which it rests on said support between said jaws, and means for maintaining the lowermost piece in said magazine above said support and at a height such that its top surface is above the top surface of said first-mentioned jaw whereby when said structure is advanced said first-mentioned jaw comes into contact with the edge of only said lowermost piece.

8. A work feeding device as called for in claim 7 which includes a drill bushing extending over said fixed jaw and containing an opening therein through which a tool may be extended to contact a piece held in said processing position.

9. A work feeding device comprising a magazine adapted to contain elongated pieces stacked end to end, reciprocating structure disposed adjacent the discharge end of said magazine and adapted to receive successive pieces thereon, spring means over said structure for engaging the sides of said pieces and for holding said pieces in upright position as they are delivered from said magazine onto said structure, and a jaw carried on said structure, said jaw being effective when

said structure is advanced to move one of said pieces forwardly out of engagement with said spring means.

10. A work feeding device comprising a magazine adapted to contain elongated pieces stacked end to end, reciprocating structure disposed adjacent the discharge end of said magazine and adapted to receive successive pieces thereon, a pair of spring fingers over said structure for engaging the sides of said pieces and for holding said pieces in upright position as they are delivered from said magazine onto said structure, a jaw carried on said structure, a second jaw opposing and cooperating with said jaw to hold one of said pieces in work-holding position, said first-mentioned jaw being effective when said structure is advanced to move one of said pieces forwardly out of engagement with said spring means and into work-holding position between said jaws, and means for actuating said reciprocating structure to advance the same to bring a piece into work-holding position and to retract the same to release said piece from such position.

11. A work feeding device comprising a magazine adapted to contain a plurality of work pieces, reciprocating structure adjacent the delivery end of said magazine, a jaw disposed in fixed position, a jaw member pivotally mounted on said reciprocating structure and adapted to receive a piece as it issues from said magazine, and means for turning said jaw member as said reciprocating structure is advanced so that said jaws face each other with one of said pieces therebetween, said jaws being mounted and arranged to tighten about said piece as said reciprocating structure is advanced to the limit of its movement.

12. A work feeding device comprising a frame, a magazine adapted to contain a plurality of work pieces, reciprocating structure mounted in said frame adjacent the delivery end of said magazine, said magazine being arranged to deliver pieces laterally onto said structure, a jaw at-

tached to said frame, a jaw member pivotally mounted on said reciprocating structure and adapted to receive a piece moving laterally from said magazine, and means for turning said jaw member and the piece therein received to present said piece for engagement with said first-mentioned jaw when said structure has advanced the limit of its forward movement.

13. A work feeding device as set forth in claim 10 12 wherein said means is operable to turn said jaw member only after said reciprocating structure has advanced to remove said piece from the delivery end of said magazine.

14. A work feeding device comprising a magazine adapted to contain work pieces in stacked relation, a reciprocating structure providing a support for the pieces when they are in processing position in said device, a pair of opposing jaws one of which is carried on said structure and the other of which is fixedly disposed with respect to said magazine, said one jaw being adapted when said structure is advanced to move a piece from said magazine into processing position where it rests on said support and is held between said jaws, said one jaw having an inclined face which extends forwardly toward the upper edge of the jaw, the upper edge of said one jaw being above the top of said piece at the point of engagement with said piece whereby said edge of the piece is restrained against movement upwardly of said one jaw when the piece is held between said jaws.

15. A work feeding device comprising a magazine adapted to contain a plurality of work pieces, reciprocating mechanism for presenting individual pieces from said magazine to processing position, said mechanism including a slide upon which said pieces rest when in processing position, and means actuated by the return movement of said reciprocating mechanism for aiding in dislodging a piece from said slide.

THEODORE E. MEAD.
